DANIEL PERRIER, OF UNIEUX, FRANCE, ASSIGNOR OF ONE-HALF TO THE FIRM COMPAGNIE INDUSTRIELLE DES MOTEURS A EXPLOSION (C. I. M. E.), OF PARIS, FRANCE, A CORPORATION OF FRANCE.

CENTRIFUGAL OIL SEPARATOR FOR USE WITH HEAT ENGINES.

Application filed April 2, 1926, Serial No. 99,428, and in Germany November 30, 1925.

This invention relates to a centrifugal oil separator for explosion engines, for internal combustion engines, for external combustion engines and generally speaking for all kinds of heat engines, for preserving the essential properties of the lubricating oil and consequently, making it last longer in use, which enables great economy of lubricant to be made.

10 Consider, for example, the case of explosion engines; it is known that the oil employment for their lubrication rapidly loses its lubricating properties for the following reasons:

15 (a) It becomes charged with particles of metal due to the wear of the members;
 (b) A certain amount of petrol which is not utilized for the combustion becomes mixed with the oil in spite of the relatively fluid tight fit of the piston rings.
 (c) It becomes charged with carbonaceous deposits from the residues of combustion.

20 (d) It is subjected to a high temperature and it is always very inadequately cooled.

By means of the apparatus which forms the subject matter of the invention the deterioration of the lubricant is obviated, due to the fact that the said lubricant is constantly and perfectly separated, while it is at the same time thoroughly cooled.

25 This apparatus is characterized essentially by the application and by the combination of the devices which are so arranged as to bring about under the influence of centrifugal force the separation of the impurities contained in the oil to be extracted.

30 Its action is as much felt on the petrol which is mixed in the oil as on the metal and carbonaceous particles which are held in suspension in it; the double separation could not be effected by means usually employed which consist in the use of filters.

35 The apparatus referred to may also be combined with a water pump and one or more oil pumps, so as to form one and the same member.

40 The present invention further relates to improvements in the rotary distributor of the separator in question with a view to improving the working of this apparatus.

45 These improvements are characterized by

the use and the combination of the following means:

1. A special arrangement of the concentric ribs forming annular chambers, which ribs may be either all rendered integral with the lower wall of the distributor or be arranged in such a way that for two adjacent ribs one is integral or virtually integral with the lower wall of the distributor and the other is formed upon the upper wall.

2. An arrangement of the orifices provided for the purpose of establishing communication between the first chamber of the separator and the distributor proper, either beyond the outer rib or in proximity to the rib nearest to the centre of the apparatus.

3. The interposition, between the first chamber or the separator specified under (2) and the distributor proper, of a plate integral or virtually integral with the bottom of the above mentioned chamber and provided for the purpose of spreading out the liquid which is to be purified.

Figure 1 illustrates diagrammatically and by way of example alone, a form of construction of the apparatus combined with a geared oil pump and a centrifugal water pump, so as to form one and the same member.

Figure 2 is a section of the same apparatus taken along the line I—I in Figure 1.

Figure 3 shows, by way of another example, a modification of the position which the upper ribs of the rotating distributor may occupy relatively to the vertical axis.

Figure 4 is a view in vertical section of another form of the rotary distributor.

Figure 5 is a similar sectional view of a modified form.

Figure 6 is a diagrammatic view of a different form in which the base of the first separating chamber is provided with a special plate for spreading out the liquid, and finally,

Figure 7 shows the arrangement of the circular channels or grooves which are concentric with the general axis of the apparatus.

The separator proper is enclosed in a casing comprising a fluid tight upper part 1 assembled upon a lower casing 2.

The upper casing 1 is provided with a pipe

3 through which the oil enters the apparatus. In this casing is mounted a shaft 4, which is hollow for a certain part of its length, through which the apparatus is driven. The internal bore 5 of this shaft communicates with the oil admission pipe 3 by means of a series of orifices 6 pierced radially in the said shaft. The bore 5 communicates with a first chamber 7 of a distributor 8 rotating with the shaft 4. The lower wall of the chamber 7 is pierced with a series of holes 9, the axes of which are on concentric circles; upon this lower face are formed ribs 10, 11, 12 and 13, arranged concentrically, which ribs may have any inclination relative to the main axis of the apparatus.

Upon the lower part, below these ribs, at a distance varying according to the speed of rotation of the apparatus, according to the delivery required from it, according to the degree of separation desired, is assembled by any means, a plate 14 provided with a series of inclined ribs 15, 16, 17 and 18. This plate 20 is also pierced with a series of holes 19, the axes of which are on concentric circles, the holes being disposed, relatively to the ribs 15, 16, 17 and 18, as shown in the drawing.

The lower plate 14 is integral or virtually integral with a shaft 20 which centers the rotating distributor either in a ball thrust bearing or in a smooth thrust bearing support, carried by the lower casing 2. This shaft 20 may also be extended as shown in 35 Figure 1 so as to drive an oil pump 21 and a water pump 22, or one only of these two pumps.

The ribs of the grooves 15 to 18 of the rotating distributor fit between other ribs forming part of the lower casing 2.

The spaces which are left between these ribs form annular divisions 23, 24, 25 and 26, which may either be separated from each other or communicate with each other, as for example the divisions 24, 25 and 26.

A circulating water chamber 27 also forms 50 a part of this lower casing and completely surrounds the last chamber 26. This circulating water chamber is provided with a water inlet 28 and a water outlet 29, communicating either directly with the water pump or with the radiator, according to the degree of cooling desired.

The division 23, which is nearest the centre of the apparatus, is provided with one or more outlet pipes 30. The divisions 24, 25 and 26, which communicate with each other are also provided with one or more outlet pipes 31.

The divisions 23 and 24 may, contrary to the arrangement shown in Figure 1, communicate with each other and be separated from the divisions 25 and 26.

The number of holes 9, of ribs 10, 11, 12 and 13, of orifices 19, of ribs 15, 16, 17 and

18, and also the number of divisions 32, 33, 34, 35 and 23, 24, 25 and 26, may vary. The dimensions and the relative positions of these different members may also be varied according to the dimensions of the apparatus and consequently according to the amount of oil which must pass through the apparatus in unit time.

The external crown of the rotating distributor is pierced with a series of orifices 36, which are closed, when the apparatus is working, by means of a collar 37 formed in two parts. The lower casing, with the inclined ribs with which it is provided, the divisions 23, 24, 25 and 26 and the outlet pipes 30 and 31 constitute the fixed receiver.

The apparatus described operates as follows:-

The lubricant to be separated, coming from either the crank case of the engine (in this case the separator would be placed under the charge of the oil casing of the engine), or a pump which forces it under pressure, arrives through the pipe 3 and enters the bore 5 of the shaft 4, through the orifices 6. The shaft 4, driven in any way, by the engine and rotating, either at the same speed in the case of a high speed engine, or at a higher speed in the case of a slow speed engine, drives the rotating distributor 8 at the same speed.

The lubricant passing through the bore 5 into the chamber 7 is immediately subjected to the action of the centrifugal force the effect of which is to produce, in the chamber 7, a separation of the parts according to their density; the metal particles and the carbonaceous particles, having the greatest density, are immediately thrown towards the outer wall of this chamber 7. The particles of less density (globules of oil proper to the lubrication, for example) enter the zone of the annular divisions 34, 33 and 32 for example, while the light particles, the petrol for example, enter the part which is nearest the axis of the apparatus.

The metallic particles remain along the external wall of the chamber 7; they cannot be ejected from the chamber because the orifices 36 are closed by the collar 37. The oil runs into the divisions 32, 33 and 34 through the orifices pierced in coincidence with these divisions. The light particles in their turn flow through the pierced orifices coinciding with the central division 38.

These different parts follow the ribs 10, 11, 12 and 13, in order to cross the lower plate 14 through the orifices 19 which are pierced in the latter.

The distance which separates the ribs 10, 11, 12 and 13 from the lower plate 14 allows a new separation of these parts to take place. The metallic particles and the carbonaceous particles which may have escaped the first separation are thrown out in the division 35.

The oils, first following the ribs 16, 17 and 18, fall into the divisions 24, 25 and 26, while the light parts following the rib 15, fall into the division 23 and are ejected through the outlet pipes 30.

The oil collected in the divisions 24, 25 and 26, that is to say the oil which is freed of all impurities, is ejected towards the oil pump through the pipe 31. This oil is cooled by cold water which circulates round the division 26 in the circulating water chamber 27.

The apparatus may be easily cleaned and freed of solid residues (metallic or carbonaceous); for this purpose it is sufficient to separate the lower casing 2 from the upper casing 1 and to loosen the closing collar 37. These residues can then pass out through the orifices 36 pierced through the outer surface of the rotating distributor.

The rotating distributor, shown diagrammatically in the figures, having two series of ribs, and consequently effecting the separation into two stages, may be constituted by two, three or four or any number of series of ribs, so that the separation is effected in a corresponding number of stages.

In the form of construction illustrated in Figure 4 the distributor proper is enclosed in a casing similar to the one shown in Figure 1, only the upper part of the casing being shown in the drawing. In this casing is mounted a shaft which is hollow over a certain part of its length and serves for the purpose of driving the apparatus.

The internal bore 5 of this shaft is placed in communication with the oil inlet 3 through a series of orifices pierced radially in the shaft. The bore 5 communicates with a first chamber 7 of the distributor turning with the above mentioned shaft. The lower wall of the chamber 7 is pierced with a series of apertures 50 the axes of which are upon a circle concentric with the axis of the apparatus.

At a certain distance from the lower face of this wall are disposed the ribs 10, 11, 12 and 13; in the example illustrated these ribs are integral or virtually integral with the plate 14 the other face of which is provided with a series of inclined ribs 15, 16, 17 and 18. The plate 14 is pierced with a series of apertures 19 and 53 the axes of which are situated upon concentric circles and which are arranged, relatively to the ribs 15, 16, 17 and 18, as shown in the drawing.

The lower plate 14 is formed upon a shaft 20 which centres the rotating distributor either in a ball thrust bearing or in a smooth thrust bearing as hereinbefore described.

As hereinbefore described, the ribs 10, 11, 12 and 13 are always integral or virtually integral with the lower wall 14 of the rotating distributor and beyond the rib 13, upon a circle concentric with the latter, are

situated the axes of the orifices 50 pierced in the lower wall 51 of the first chamber 7 of the distributor. The wall 14 is itself pierced with a series of orifices 19 the axes of which are upon a circle situated in the compartment or chamber 35 at a varying distance from the wall 39. Another series of orifices 52 is pierced in the central part of the wall 14 which merges into the central chamber 33.

According to the nature of the mixture to be separated and the degree of separation desired other series of orifices may be pierced in the wall 14, such as the orifices 53 which establish communication between the chamber 33 and the fixed receiver of the apparatus.

The operation of the apparatus shown in Figure 4 is as follows:

The liquid to be separated undergoes a first separation in the chamber 7 and this operation results in a certain amount of the solid particles which are held in suspension in the liquid being deposited upon the outer wall of the said chamber 7. As regards the liquid particles, these descend through the orifices 50 into a chamber 35, undergoing a fresh separation, by density. The solid particles which may still remain in suspension in the liquid are then deposited along the wall 39. The heaviest liquid particles are exhausted through the orifices 19. On the other hand the particles of small density follow the path indicated in dot and dash lines in Figure 4 in order to pass then into the chamber 38 after having deposited the last solid impurities they may still have contained along the ribs 13, 12, 11 and 10.

The liquid, completely freed from impurities is discharged into the fixed receiver through the orifice 52.

When the liquid which is to be purified contains several liquid substances of different densities which it is desired to collect separately, the latter may be removed through the series of orifices situated for example, in the annular chamber 33.

In the modification shown in Figure 5 the ribs 10 and 12 are integral or virtually integral with the wall 14, while the other ribs 11 and 13 are, on the contrary, formed upon the lower wall 51 of the chamber 7. In other words, for two consecutive ribs 10 and 11, one of the ribs is integral or virtually integral with the wall 51 while the other is formed upon the wall 14.

The operation of the apparatus shown in Figure 5 is the same as that of the one shown in Figure 4. However, the path traversed by the liquid particles is different. As shown in this figure, the liquid particles first circulate along the wall 39 in order to reach the lower part of the rib 13; they circulate upwards along the rib 13 in order to travel subsequently, in the opposite direc-

tion, along the rib 12; they then move upwards along the rib 11 and then descend along the rib 10 which forms a part of the chamber 38. It is from this chamber that 5 the liquid of small density flows into the corresponding part of the fixed receiver.

In the modified form shown in Figure 6, the liquid issues from the first separation chamber 7 through the orifices 54 the axes 10 of which are arranged upon a circle situated at a very small distance from the general axis of the apparatus, that is to say upon a circle the radius of which is smaller than that of the circular rib 10 forming the 15 wall of the central chamber 38 of the distributor. Upon issuing from these orifices the liquid is spread out in thin sheets upon a plate 55 integral or virtually integral with the wall 51, after which this liquid follows 20 exactly the same path as in the form shown in Figure 4.

Finally, the improvement shown in Figure 7 consists in replacing the series of orifices disposed upon circles concentric with 25 the circular ribs, by circular slots 19' or 51'.

By means of the arrangement shown in Figures 4 to 6 the result is obtained of increasing by a large amount the path of the 30 liquid particles which it is desired to separate and consequently the surface wetted by these particles even though the space occupied by the apparatus is small. Thus with an apparatus constructed according to the 35 arrangement shown in Figures 4, 5 and 6 and divided by concentric ribs 10, 11, 12 and 13 into five compartments 38, 32, 33, 34, 35, it is possible to obtain the same useful effect as with a centrifugal tubular separator 40 the separating bowl of which has a length five times as great.

The apparatus, the mode of operation of which has been hereinbefore described may be mounted on an engine in different ways:

(a) It may be combined in one and the same member with one or two oil pumps and a water pump, one of the oil pumps drawing the oil from the crank case and forcing it under pressure to the separator, while the 50 second draws oil from the separator and feeds it to the parts to be lubricated.

(b) It may be mounted separately and receive the oil to be separated from an independent pump and eject the separated oil 55 by a pump which is also independent. It may receive its cooling water from an independent water pump, or else from any kind of radiator.

(c) It may be so mounted on the engine 60 that it receives the oil to be separated by gravity from the crank case.

(d) Finally it may be driven by the engine in any manner.

The apparatus is not only applicable to 65 explosion engines, but also to any internal

combustion engines (Diesel engines, semi-Diesel engines, heavy oil engines of any type), to all heat engines (steam engines, steam turbines, for example). In the case of steam engines and steam turbines, the oil, 70 having completed a lubricating circuit, contains in suspension small drops of water which it has collected from contact with the steam and from the lubricating in these types of machines; the apparatus enables 75 this water to be separated from the oil.

What I claim is:

1. A centrifugal lubricating oil separator for all heat engines, comprising a rotating distributor having a chamber into which the 80 oil first passes for undergoing a first separation of the impurities, the lower wall of said chamber being provided with a series of orifices, the axes of said orifices being disposed in concentric circles, a series of concentric ribs depending from said lower wall forming a series of annular separating chambers with which said series of orifices communicate, another wall enclosing said ribs and annular chambers, said other wall 85 being provided with orifices, and a second set of ribs depending from said lower wall in operative relation to said last mentioned orifices, and a fixed receiver into which the 90 lowermost ribs on the distributor extend. 95

2. A centrifugal lubricating oil separator for all heat engines, comprising a rotating distributor having a chamber into which the oil first passes for undergoing a first separation of the impurities, the lower wall of 100 said chamber being provided with a series of orifices, the axes of said orifices being disposed in concentric circles, a series of concentric ribs depending from said lower wall forming a series of annular separating chambers with which said series of orifices communicate, another wall enclosing said ribs and annular chambers, said other wall 105 being provided with orifices, and a second set of ribs depending from said lower wall in operative relation to said last mentioned orifices, and a fixed receiver having a set of annular ribs interleaving with the lowermost ribs upon the distributor. 110

3. An oil separator as claimed in claim 1, 115 wherein the generating lines of the series of orifices are inclined at an angle to the main axis of the apparatus.

4. An oil separator as claimed in claim 1, 120 in which the fixed receiver includes ribs inclined to the axis of the apparatus and ribs parallel to the axis of the apparatus provided upon said fixed receiver, spaces being left between said ribs forming divisions into which the lowermost ribs on the distributor extend. 125

5. An oil separator as claimed in claim 1, 130 in which the fixed receiver includes ribs inclined to the axis of the apparatus and ribs parallel to the axis of the apparatus pro-

vided upon said fixed receiver, spaces being left between said ribs forming divisions which communicate with each other.

6. An oil separator as claimed in claim 1, including in combination with the fixed receiver, a circulating water casing in which receiver the oil having been freed of all its impurities is cooled by means of said circulating water.

10 7. An oil separator as claimed in claim 1, wherein the apparatus is provided with a plurality of series of ribs and orifices the number of said series of ribs and orifices corresponding to the number of stages in 15 which it is desired to carry out the separation.

8. An oil separator as claimed in claim 1, further comprising a collar normally closing 20 peripheral apertures in said distributor, said collar completely surrounding said rotating distributor, said collar being removable from said apertures adapted to enable solid particles separated from the oil and which have lodged in said apertures to be rapidly ejected 25 by centrifugal force.

9. An oil separator as claimed in claim 1, further comprising an oil pump and a water pump, said oil pump and said water pump being united so as to form one whole.

30 10. A centrifugal lubricating oil separator for all heat engines, said separator comprising a rotating distributor adapted to effect the separation, by centrifugal force, of the impurities contained in the oil, said rotating distributor including a chamber, in which chamber is effected a first separation of the impurities, one wall of said chamber formed with a series of orifices, the axes of said orifices being disposed on concentric circles 35 and said orifices establishing communication between said chamber and the distributor proper, a series of concentric ribs provided upon the lower wall of said distributor

proper, said ribs forming annular compartments.

45

11. An oil separator as claimed in claim 10, further comprising concentric ribs upon the upper wall of said chamber, the arrangement of the ribs being such that for two adjacent ribs one is provided upon the lower 50 wall and the other upon the upper wall of said distributor proper.

12. An oil separator as claimed in claim 10, wherein the orifices adapted to establish communication between said first chamber 55 of the separator with the distributor proper are formed beyond the outer rib.

13. An oil separator as claimed in claim 10, wherein the orifices adapted to establish communication between said first chamber 60 of the separator with the distributor proper are formed in proximity to the rib nearest the centre of the apparatus.

14. An oil separator as claimed in claim 10, wherein a plate is interposed between 65 said first chamber and the distributor proper, said plate being provided upon the base of said chamber and adapted to spread out the liquid which is to be purified by separation.

70

15. A centrifugal lubricating oil separator for all heat engines, said separator comprising a rotating distributor adapted to effect the separation, by centrifugal force, of the impurities contained in the oil, a fixed 75 receiver combined with said distributor said distributor being formed with circular slots concentric with the general axis of the apparatus and adapted to establish communication between the various parts of the distributor and to discharge the products of the separation into said fixed receiver.

80

In testimony whereof I have signed my name to this specification.

DANIEL PERRIER.
